GRINDING MACHINE

Frederick A. Ward, Detroit, Mich., assignor to
 The Gear Grinding Machine Company, Detroit,
 Mich., a corporation of Michigan

Application June 30, 1930, Serial No. 465,048

4 Claims. (Cl. 51—92)

The invention relates to the art of form grinding and has for its object the extension of this general method to the grinding of articles of a different character than those heretofore operated upon.

In the present state of the art grinding machines have been devised in which a formed grinding wheel is successively presented to a series of surfaces in the work to be finished to a corresponding form. Where these successive surfaces are so arranged about a common axis of rotation that they may be brought into coincident positions, the work may be performed without difficulty. For instance, in the grinding of a gear each of the teeth may be successively ground to a predetermined form by indexing the work and relatively reciprocating the same in relation to the grinding wheel. On the other hand, where the surfaces to be ground are in dissimilar relations this method is not applicable.

The present invention provides a means for the grinding of articles having a series of surfaces, all of which can not be brought into coincident positions by rotation about a single axis, and the invention therefore consists in the novel apparatus as hereinafter set forth.

In the drawings:

Figure 1 is a plan view of my improved machine;

30 Figure 2 is an end elevation thereof;

Figure 3 is a side elevation;

Figures 4, 4A, 4B are respectively a plan view, side elevation and end elevation of a universal joint member which is a specific article that may be ground by my improved method;

35 Figure 5 is a cross section through the indexing mechanism;

Figure 6 is a sectional side elevation of the trimming mechanism and

40 Figure 7 is an enlarged cross section on line 7—1 of Figure 6.

While my improved means is applicable to grinding of various articles, I have illustrated in Figures 4, 4A and 4B one specific article, viz: a member of a universal joint which may be finished in this manner. This member has a shank A at one end of which is a head B having a series of spaced prongs C for inter-engaging correspondingly formed prongs on a cooperating member. Each of the prongs has arranged upon opposite sides thereof segmental cylindrical races for receiving balls placed intermediate the prongs and which constitute a pivotal and substantially frictionless joint therebetween. These races 55 have their axes non-parallel to the axis of the

shank A but all of said axes intersect in a common point which is also in the axis of the shank A. Thus as illustrated in Figure 4, D and D' are ball races of segmental cylindrical form, the axes of which intersect the common point E in the axis of the shank A. It will be noted, however, that the races D on one side of each of the prongs C never assume coincident positions with the races D' upon opposite sides of said prong, and therefore it is impossible to successively place 10 the races D and D' in operative relation to a grinder wheel by a mere rotation about a single axis such as that of the shank A. It is, however, possible to arrange the axis of the shank A in such relation to the plane of a formed 15 grinder wheel that all of the races of one of the series D or D' may be brought into the same relation to the grinder wheel by rotation about the axis of the shank A. Thus as illustrated in Figures 4, 4A and 4B, the axis D² E of the races D 20 lie in the plane of the rotation of the grinder wheel F, so that a relative reciprocation of the work and the grinder wheel parallel to such axis will cause the formed cross-sectional contour of the wheel to trace the race D. Each of the other 25 races D may be successively placed in the same position by a rotation of the shank A, but none of the races D' can be so registered. If, however, the axis of the shank A should be revolved around the point E into the dotted position A', 30 then the race member D' will have its axis coincident with the axis D² E of the race member D and will be in the same operative relation to the grinder wheel F.

In view of the geometrical relations just described, it is evident that to form grind both series of races D, D', requires the rotation of the work not only about the axis of the shank but also about a transverse axis which passes through the point of intersection of the axes of all of the races and that of the shank. I have therefore devised a construction of grinding machine which permits of such adjustment and which is of the following construction.

The frame of the machine G has supported thereon the reciprocating carriage H which may be driven by any suitable automatic mechanism (not shown). Adjacent to this carriage H is an upward extension I of the frame having slidably secured thereto the vertically movable cross head J. The head J has bearings J' for an arbor K having its axis extending perpendicular to the axis of movement of the carriage H. On this arbor is a grinding wheel L which is suitably 55

fashioned by the operation of a trimmer as hereinafter described.

Work holder

5 Upon the carriage H is mounted a work holder M which is adapted to receive the shank A of the universal joint member and to hold the same in operative relation to the grinding wheel. This work holder M comprises a member N which is 10 pivotally mounted upon the carriage H so as to be capable of a considerable angular adjustment about the axis of its pivot which is perpendicular to the plane of movement of the carriage. The member N has mounted thereon the upwardly 15 extending housing O in which the work holder M is journaled concentric with the axis of the shank A. The housing O also contains an index mechanism by which the holder M may be rotated to predetermined positions as hereinafter described.

With the construction as thus far described it will be understood that the axis of the work holder M and of the shank A engaging the same lies in a horizontal plane and that it may be adjusted in 25 this plane from the angular position shown in full lines in Figure 1 to the position indicated in dotted lines in the same figure. The amount of such angular movement and the exact terminal positions thereof is determined by stops P and P' 30 shown as adjustable screws and thus the axis of the holder M may be set at an exactly predetermined angle to the plane of the grinding wheel in both of said positions. It will be further understood that the axis of the holder M lies in a 35 horizontal plane in all positions of adjustment and that each of the axes of the races may be adjusted to lie in this same horizontal plane. Consequently the reciprocating movement of the table H will move the head B of the universal joint past the 40 grinding wheel with one of the race members in position to be ground by said wheel while passing the same. Through the index mechanism to be hereinafter described, the head M may be relatively adjusted to bring the race members successively 45 into operative relation to the grinding wheel until the entire series is ground, after which by adjusting the member N into the dotted position, all of the races D' may be in a similar manner successively ground.

50

Trimming mechanism

The accuracy of the work performed depends upon the exact location of the form grinding wheel in relation to the path of the work. This exact location is obtained first by the setting of the wheel and arbor and second, by the forming of the wheel through operation of the trimming mechanism. This trimming mechanism Q is mounted on one 55 end of the table H so that periodically it may be carried by said table into operative relation with the grinding wheel. The essential features are first, that the trimmer in fashioning the cross sectional contour of the grinder should rotate about the exact axis of the race when in grinding 60 position; second, that the trimming point should be an exactly predetermined radial length from this axis. The trimmer comprises a shaft Q' which is journaled in bearings in a head Q² with its axis horizontal and parallel to the direction 65 of movement of the carriage H. The forward end of the shaft Q' is provided with a tapering socket to receive the correspondingly tapered end of the trimmer tool Q³. This tool has an off-set portion Q⁴ provided with a radial aperture receiving the 70 trimmer point holding member Q⁵ which is 75

clamped in different positions of adjustment by the set screw Q⁶. Thus the adjustment of the member Q⁵ will determine the radial distance of the trimmer point from the axis of the shaft Q'. To correctly position this axis of the shaft so as to align the same with the correct axis of the race member to be ground, there is provided adjustments for the head Q² vertically and transversely. The vertical adjustment is secured by mounting the head Q on an inclined base Q⁷ to which it is 10 adjustably clamped by headed bolts Q⁸ engaging a longitudinal slot in said base. Adjusting screws Q⁹ are arranged at opposite ends of the base Q to engage the head Q² and to move the same either upward or downward on the inclined base. During this movement the head Q² is held from any transverse movement by tongue or key members Q¹⁰ thereon fitting the longitudinal slot in the base Q⁷. Thus the effect of adjusting the head Q² up or down the incline is to raise or lower the 20 axis of the shaft Q'.

To adjust the axis of the shaft Q' transversely the base member Q⁷ is mounted on the sub-base member Q¹¹ and is provided with a tongue or key portion Q¹² fitting the transverse slot in said member Q¹¹. Adjusting screws Q¹³ engaging the threaded bearings in upwardly extending ears Q¹⁴ on the sub-base Q¹¹ serve to move the base Q⁷ laterally and headed clamping screws Q¹⁵ secure the members Q⁷ and Q¹¹ in fixed relation after 30 adjustment. Thus the axis of the shaft Q' may be adjusted vertically and transversely into an exactly predetermined position and the movement of the table H will carry the trimmer to the position where the trimming point is in the vertical 35 plane of the arbor K. In this position a rocking of the shaft Q' by a handle Q¹⁶ will move the trimmer point in an arc concentric with the axis of the shaft and of exactly predetermined radius, thereby fashioning the grinding wheel L to corresponding form.

Index mechanism

The work holder M is a rotary member journaled in bearings in the housing O and provided 45 with a socket for receiving the shank A of the work. Mounted on the member M within the housing O is an index disk M' having notches M² in the periphery thereof. These notches are engaged by a tapering detent M³ on a rockable dog 50 M⁴ pivoted within the housing and a spring pressed plunger M⁵ operates to yieldably hold the detent in engagement with the notch. Adjacent and secured to the index disk M' is a ratchet wheel M⁶ provided with notches M⁷ corresponding 55 in number to the notches M². M⁸ is a sleeve rotatable upon the member M and extending out through the bearing in the housing O. This sleeve has within the housing a cam portion M⁹ which is adapted to engage with a roller M¹⁰ on the dog M⁴ to lift the detent M³ out of engagement with the notch M². The cam M⁹ also carries a pawl M¹¹ which is engageable with one of the notches M⁷ of the ratchet wheel M⁶ and in the return rotation of the sleeve M⁸ will move said 60 ratchet wheel and the index disk M' until the detent M³ engages another notch M². The sleeve M⁸ is actuated by a handle M¹² on the outside 65 of the casing O.

Complete operation

In the complete operation of the machine the work holder and trimming mechanism being first 70 suitably adjusted, the operator first trims the grinding wheel L by moving the carriage H to 75

bring the trimmer point into the vertical plane of the axis of the arbor K. The arbor may then be adjusted downward to bring the grinding wheel L into operative relation to the trimmer which 5 fashions the cross section of the wheel to the exact arc of the races D and D'. One of the universal joints having its shank engaged with the work holder M, the carriage H is reciprocated to move the head B past the grinder wheel, there- 10 by grinding one of the raceways in one of the prongs C. If the amount of stock to be removed in finishing this raceway is more than can be accomplished by one reciprocation of the grinder, the arbor K can first be raised and then fed 15 downward after each reciprocation until the finish position is attained. The adjustment of the arbor is accomplished by a hand wheel R which through the medium of suitable gearing (not shown) rotates the feed screw R' to raise or lower 20 the head J upon the frame extension I.

After the completion of the grinding of the raceways the work is adjusted through the index mechanism operated by the handle M¹² to bring another raceway into operative relation to the 25 grinding wheel and these operations are repeated until all of the raceways D have been ground. The operator then adjusts the work holder by swinging the member N upon the vertical pivot N' to assume the position shown in dotted lines in 30 Figures 1 and 4. It is then clamped by the clamping screw N² to prevent accidental displacement and the grinding is repeated with reference to the raceways D'. Thus in the finished product 35 all of these raceways will be cylindrical segments of an exactly predetermined radius, the axes of all of which will intersect in a common point E, also lying in the axis of the shank A.

What I claim as my invention is:

1. A grinding machine comprising a frame, 40 a grinding wheel and a table mounted on said frame in relatively reciprocating relation, a member mounted on said table to be angularly adjustable thereon about a vertical axis at the central portion of the table, means for limiting the angular adjustment of said member, a work holder rotatively mounted upon said member eccentric to said vertical axis with its axis of rotation in a plane parallel to the plane of said table, the angular adjustment being through an arc greater 45 than ninety degrees (90°) to present opposite portions of the work in said work holder to operative engagement with the tool, and an index mechanism cooperating with said rotary work holder.
2. A grinding machine comprising a frame, 50 a grinding wheel and a table mounted on said frame in relatively reciprocating relation, a member mounted on said table to be angularly adjustable thereon about a vertical axis at the central portion of the table, a rotary work holder

5 mounted on said member eccentric to said vertical axis with its axis of rotation in a plane parallel to the plane of said table, the angular adjustment being through an arc of greater than ninety degrees (90°) to present opposite portions 10 of the work in said work holder to operative engagement with the tool, an index mechanism cooperating with said rotary work holder, and means for limiting the angular adjustment of 15 said member to arrange the axis of said rotary work holder at the two extremes of its adjustment at equal and opposite angles to the direction of relative reciprocation of said grinding wheel and table.

3. A grinding machine comprising a frame, a 20 carriage mounted for reciprocation thereon, a formed grinding wheel mounted on said frame with its plane of rotation parallel to the direction of reciprocation of said carriage, the cross sectional contour of said grinding wheel being arcuate, a member mounted on said carriage to be angularly adjustable about a vertical axis at the central portion of the carriage, a rotary work holder mounted on said member eccentric to said vertical axis with its axis of rotation in a plane 25 parallel to the plane of said carriage and passing through the center of the arcuate cross section of said grinding wheel, the angular adjustment being through an arc of greater than ninety degrees (90°) to present opposite portions of the 30 work in said work holder to operative engagement with the tool, and an index mechanism cooperating with said rotary work holder.

4. A grinding machine comprising a frame, a 35 carriage mounted for reciprocation thereon, a formed grinding wheel mounted on said wheel with its plane of rotation parallel to the direction of reciprocation of said carriage, a cross sectional contour on said grinder wheel being arcuate, a member mounted on said carriage to be angularly 40 adjustable about a vertical axis lying in the same plane of reciprocation as the center of arcuate cross section of said grinding wheel, a rotary work holder mounted upon said member with its axis of rotation intersecting said vertical axis and located in a plane parallel to the plane of movement of said carriage, the angular adjustment being through an arc of greater than ninety degrees (90°) to present opposite portions of the 45 work in said work holder to operative engagement with the tool, index mechanism for said rotary work holder, and means for limiting the angular adjustment about said vertical axis of said member mounted on the carriage, so that the angle of the axis of said work holder to the 50 direction of reciprocation at one limit is equal and opposite to that at the other limit.

FREDERICK A. WARD.
